(21) Appl. No.: **29/555,944**

CLAIM

(22) Filed: **Feb. 25, 2016**

The ornamental design for a rear combination lamp for an automobile, as shown and described.

(30) **Foreign Application Priority Data**

Oct. 30, 2015 (KR) 30-2015-0054626

DESCRIPTION

(51) **LOC (10) Cl.** **26-06**

FIG. 1 is a perspective view of a rear combination lamp for an automobile according to the present invention.

(52) **U.S. Cl.**

FIG. 2 is a front view of the rear combination lamp for an automobile of FIG. 1.

USPC **D26/28**

FIG. 3 is a rear view of the rear combination lamp for an automobile of FIG. 1.

(58) **Field of Classification Search**

FIG. 4 is a left side view of the rear combination lamp for an automobile of FIG. 1.

USPC D26/28-36; 362/80-83, 267-269,

FIG. 5 is a right side view of the rear combination lamp for an automobile of FIG. 1.

362/459-468, 475-478, 485-487

FIG. 6 is a top view of the rear combination lamp for an automobile of FIG. 1; and,

CPC F21S 48/00; F21S 48/10; F21S 48/115;

FIG. 7 is a bottom view of the rear combination lamp for an automobile of FIG. 1.

F21S 48/225; F21S 48/1233; F21S

48/1266; F21S 48/1388; F21S 48/2268;

F21V 21/04
